[57] **CLAIM**

The ornamental design for a showerhead, as shown and described.

DESCRIPTION

FIG. 1 is a front perspective view of a showerhead showing my new design;

FIG. 2 is a rear perspective view thereof;

FIG. 3 is a front elevational view thereof;

FIG. 4 is a side elevational view thereof; and,

FIG. 5 is a rear elevational view thereof.

The broken line showing of the face plate in FIGS. 1 and 2 is for purposes of illustration only and forms no part of the claimed design.
